Primary Examiner — Mitchell Siegel(74) Attorney, Agent, or Firm — Oliff PLC(57) CLAIM

The ornamental design for a golf club head, as shown and described.

DESCRIPTION

FIG. 1 is a rear, heel-side, top perspective view of the golf club head;

FIG. 2 is a rear elevational view thereof;

FIG. 3 is a top plan view thereof;

FIG. 4 is a heel-side elevational view thereof;

FIG. 5 is a toe-side elevational view thereof;

FIG. 6 is a bottom plan view thereof; and,

FIG. 7 is a rear, toe-side, bottom perspective thereof.

The dot-dash chain lines illustrate the boundaries of the claimed design and form no part of the claimed design. The broken lines illustrate environmental subject matter and form no part of the claimed design.

1 Claim, 6 Drawing Sheets(56)
